UNITED STATES PATENT OFFICE.

SWITS CONDÉ, OF OSWEGO, NEW YORK.

DESIGN FOR KNIT FABRIC.

SPECIFICATION forming part of Design No. 11,669, dated March 9, 1880.

Application filed February 14, 1880. Term of patent 7 years.

To all whom it may concern:

Be it known that I, SWITS CONDÉ, of Oswego, in the county of Oswego, in the State of New York, have invented new and useful improvements in Design for Knit Fabric, of which the following, taken in connection with the accompanying drawing, is a full, clear, and exact description.

The accompanying drawing represents a portion of knitted fabric figured according to my design, the said fabric being intended for the manufacture of suitings, underwear, and wearing-apparel generally.

a a and *b b* denote stripes of different colors, said stripes being arranged alternately and parallel to each other and diagonal or obliquely on the fabric. Either or both of the said stripes

may consist of one or more colors, to suit the fancy or fashion of the times.

What I claim is—

The design for knitted fabric, consisting of the parallel stripes *a* and *b*, of different colors, and arranged oblique on the fabric, substantially as shown.

In testimony whereof I have hereunto signed my name and affixed my seal, in the presence of two attesting witnesses, at Oswego, in the county of Oswego and State of New York, this 10th day of January, 1880.
